UNITED STATES PATENT OFFICE.

JOSEPH W. LEACH, OF BOSTON, MASSACHUSETTS, ASSIGNOR OF ONE-HALF TO SEWALL A. DINSMORE, OF SOMERVILLE, MASSACHUSETTS.

SHOE.

No. 922,164.

Specification of Letters Patent.

Patented May 18, 1909.

Application filed September 14, 1908. Serial No. 452,847.

To all whom it may concern:

Be it known that I, JOSEPH W. LEACH, of Boston, county of Suffolk, State of Massachusetts, have invented an Improvement in Shoes, of which the following is a specification.

This invention relates to shoes, and particularly to low-cut shoes especially adapted for use as bathing shoes.

10 The object of the invention is to produce a shoe without a front opening, which may be easily drawn onto the foot of the wearer and which will snugly fit the foot.

15 Figure 1 is a side elevation of a shoe embodying this invention. Fig. 2 is a transverse vertical section of the shoe shown in Fig. 1, taken on the dotted line 2—2, it being broken away at one side. Fig. 3 is a transverse vertical section of the shoe shown 20 in Fig. 1 taken on the dotted line 3—3, it being broken away at one side. Fig. 4 is a detail of one of the parts composing the upper.

25 The upper comprises two pieces *a* and *b* of textile material, such for instance as knitted fabric known in the trade as stockinette. These pieces are similarly shaped and each comprises a vamp and quarter portions, see Fig. 4. The two pieces are secured together by rubber cement, which entirely 30 covers the adjacent sides of the pieces, and *c* represents the interposed layer of rubber cement.

At the top of the upper around the opening for the insertion of the foot, a rubber band *d* of substantial thickness is inserted 35 between the two pieces *a* and *b*.

At the heel end of the upper a counter *e* of textile material is inserted between the two pieces *a* and *b*, which extends from the 0 top to the bottom thereof, or thereabouts, and said counter is secured to said pieces by rubber cement laid upon both sides of it, so that the heel end of the upper is stiffened materially by the additional rubber cement 5 which is interposed between the two pieces *a* and *b*, and also by the counter, and a suitable shape is given to the heel end of the upper which is permanently maintained. Said counter when interposed between the two 10 pieces *a* and *b* extends across the opening formed by the meeting edges of the ends of the quarter pieces, and thereby securely holds said edges together. The upper, when completed, is applied to a last having thereon an inner sole *f* composed of textile mate-

rial, the edge of the upper extending over and being secured to the edge of the inner sole by rubber cement, and then the outer sole *g* is applied which is also composed of textile material, and said outer sole is secured to the upper and inner sole by rubber cement. The outer sole has on its under or exposed side by a layer of rubber *g'*.

6 The shoe when completed is placed in a vulcanizer and vulcanized, and the interposed layers of rubber cement and rubber become integrally formed, and as a result a very strong and durable shoe is produced which may be easily applied to the foot of the wearer and which will snugly cling to 7 the foot and will maintain its shape. The rubber is used in the form of cement merely for ease in application, but it may be used in any other form.

It will be noted that when the shoe is vulcanized the counter is embedded in the interposed rubber layer connecting the elastic band at the top of the upper with the heel.

Having thus described my invention, what I claim as new and desire to secure by Letters Patent is:—

1. A shoe consisting of an upper composed of two similarly shaped pieces of textile material, each comprising a vamp and quarter pieces, the edges of the quarter pieces meeting at the heel, a layer of rubber interposed between said pieces by which they are attached together, a counter interposed between said pieces at the heel which is embedded in an interposed layer of rubber thereat, an inner-sole of textile material and an outer-sole of textile material, and an interposed layer of rubber between said soles in which the edge of the upper is embedded, and by which said upper, inner-sole 85 and outer-sole are attached together, and a layer of rubber on the exposed side of said outer-sole, the shoe being vulcanized and the several layers of rubber being integrally formed, substantially as described.

100 2. A shoe consisting of an upper composed of two similarly shaped pieces of textile material, each comprising a vamp and quarter pieces, the edges of the quarter pieces meeting at the heel, a layer of rubber interposed between said pieces by which they are attached together, a narrow band of rubber interposed between said parts at the top, a counter interposed between said pieces at the heel which is embedded in the 110

interposed layer of rubber thereat, and extends to the rubber band, an inner-sole of textile material and an outer-sole of textile material, and an interposed layer of rubber 5 between said soles in which the edge of the upper is embedded, and by which said upper inner-sole and outer-sole are attached together, and a layer of rubber on the exposed side of said outer sole, the shoe being 10 vulcanized and the several layers of rubber

being integrally formed, substantially as described.

In testimony whereof, I have signed my name to this specification, in the presence of two subscribing witnesses.

JOSEPH W. LEACH.
